UNITED STATES PATENT OFFICE.

JOHN BURMEISTER, OF MINNEAPOLIS, MINNESOTA.

GARMENT-SUPPORTER.

1,227,112.

Specification of Letters Patent.

Patented May 22, 1917.

Application filed July 14, 1916. Serial No. 109,381.

To all whom it may concern:

Be it known that I, JOHN BURMEISTER, a citizen of the United States, residing at Minneapolis, in the county of Hennepin and 5 State of Minnesota, have invented certain new and useful Improvements in Garment-Supporters, of which the following is a specification.

This invention relates to improvements in 10 garment supporters, and is designed particularly for supporting hose and other articles of wearing apparel.

Heretofore, hose supporters commonly in use have been so constructed that when applied to the stockings or other clothing they 15 present thick bunches or lumps, which often show through the relatively thin outer garments. Furthermore, nearly all the former supporters comprise two separate members, 20 one of which carries a stud, usually covered with rubber or cloth, the other member being a detachable loop, which is placed over the stud and the portion of the hose engaged by the stud, and is then manipulated in the 25 usual manner for securing all of the parts together. These studs are relatively small and often pierce and mutilate the hose, and besides, the loop and stud members being 30 separate parts, sometimes let-go, and therefore, are not entirely dependable. The object of the present invention is to provide a 35 clasp for garment supporters, which consists of a pair of tweezer-like spring jaws, normally open when idle, between which the 40 stockings or other clothing are disposed, the said jaws capable of being compressed and interfitted for providing a relatively thin body which lies flat against the person. A further object is to provide novel, simple 45 and effective means for compressing and holding the jaws of the clasp in the engaged position. All of the said parts being constructed and arranged particularly for producing a clasp which is substantially flat 50 and therefore invisible when worn beneath a relatively thin outer garment. And a further object is to provide novel and simple means for shielding the metal parts of the clasp from contact with the body of the wearer.

I attain these objects by the means set forth in the detailed description which follows, and illustrated in the accompanying drawing, in which—

55 Figure 1 is a front elevation of the clasp

in the open position, attached to an elastic or suspender.

Fig. 2 is an edge view of the same.

Fig. 3 is a similar edge view; the clasp being closed. 60

Fig. 4 is a rear side elevation.

Fig. 5 is an enlarged longitudinal section, taken on line 5—5 of Fig. 4.

Fig. 6 is a front face view of the clasp alone. 65

Figs. 7 and 8 are respectively front and edge views of the locking sleeve.

In the drawing, the clasp or clamp comprises the tweezer-like arms or shanks 2 and 2', having at their corresponding ends cup-shaped jaws 3—3'. These parts are preferably made of a single strip or piece of spring steel or other suitable material, which is folded at 4, for forming an eye or loop, and at the same time giving to the clasp a certain amount of spring or flexibility, which tends to normally spread the jaws apart when the device is not in use. The cupped portion of jaw 3 is smaller than the corresponding portion of jaw 3', and is intended to be received within the latter telescopically when the arms are compressed or closed upon each other (see Figs. 3 and 5) for gripping and holding a garment or hose, as 6, which is inserted between the jaws 3—3' while they are spread apart, as shown in Fig. 2. 7 represents a sleeve or slide which encompasses the arms or shanks 2—2', between the jaws and loop 4, the said sleeve preferably being flattened to conform to the shape of the said arms. The opposite, or front and rear sides of the sleeve at its forward end are provided with integral lugs or guards 7', which overlap the jaws 3—3' when the latter are in the closed position. 80

The jaws 3—3' are preferably wider than the arms 2—2', in order to provide each with the cup for receiving portions of the garment. The bent up edges or flanges extend along each side and across the ends of the jaws 3—3', so as to afford a relatively long gripping or engaging surface for each jaw, whereby when the jaws are brought together by the forward or downward sliding of the sleeve 7, the fabric of the hose or other garment is engaged to the full extent of the flanges or lips of the jaws. Thus, when the jaw 3 enters the jaw 3' the fabric is crimped (see Fig. 5) in the form of the letter U, which affords an adequate grip or 100 105 110

hold on the garment. The lugs or guards 7' of the sleeve extend partway over the outer faces of the jaws 3—3' and tend to prevent the latter from springing apart under any of the usual strains while the device is in use. To increase the grip and adhesion of the device, as well as to prevent the metal of the clasp from contacting with the body or underclothing of the wearer, the jaw 3' 10 has its inner face covered with cloth or rubber 8, which is extended over the end portion of the flange, then folded backwardly against the outer face of the jaw, and is secured to said jaw by threads or other suitable securing means, as 9. The jaw 3' is 15 perforated at 9' to facilitate the sewing of the shield 8. The cloth or rubber shield 8 is again extended longitudinally, passing loosely beneath the sleeve 7 and the loop or eye 4, and its opposite end is folded over a rod or wire 10, which is carried by a suspender loop 11, the shield 8 being secured to the rod 10 by sewing or other suitable means, as shown at 12. The loop 11 is otherwise 20 of the usual construction, having a contracted portion 11' which passes through and pivots in eye 4. 13 represents an elastic or suspender, which is attached in the usual manner to the enlarged portion of loop 11. 25 In practice the suspenders 13 are usually detachably secured to the corsets or other parts of the clothing, and are adjustable by means of buckles 14.

The operation of my improved garment 30 clasp is as follows:

The top of the stocking or the like portion of another garment is inserted between the open jaws 3 and 3' (Fig. 2) of the clasp. The jaws are then compressed by the thumb 40 and finger sufficiently to hold the parts in place. The sleeve 7 is then moved downwardly over the arms 2—2', by applying the thumb to the upper end, as at 15. The sleeve should be slid downwardly until the 45 opposite edge portions 16 approach closely

to the upper ends of the flanges of the jaws (see Fig. 3). This operation tightly compresses the jaws together, jaw 3 within jaw 3', and clamps and securely holds the fabric of the garment, as described. To release the 50 stocking, the jaws are compressed with the thumb and fingers, and the sleeve 7 is moved toward the loop 4, by applying pressure against the end of lug 7'. This allows the jaws to spring apart, as in Fig. 2. 55

My garment clasp is extremely simple in construction and inexpensive to make. The interfitting or telescoping jaws grip the fabric of the garment in a manner that holds against any strain to which the device may 60 be subjected, and the whole device is so constructed and arranged that it is flat and relatively thin and has no projecting parts which render it visible when worn beneath the relatively thin outer garments. 65

Having thus described my invention, what I claim as new and desire to secure by Letters Patent, is—

A garment supporter comprising an integral resilient metallic strip being bent 70 upon itself to provide a pair of adjacent resilient arms, one of which is slightly longer than the other, the arms at their free end portions being materially widened and having down-turned flanges along each side and 75 across the edge to form cup-shaped jaws, one adapted to receive the other and crimp therebetween a portion of a garment, and means for drawing said cup-shaped ends together comprising a slidable continuous 80 member encompassing the arms and having frictional contact therewith, said member being provided with relatively long forwardly extending inclined lip portions each projecting a substantial distance from the body 85 thereof, and engaging the surfaces of the arms, substantially as described.

In testimony whereof I affix my signature.

JOHN BURMEISTER.
